UNITED STATES PATENT OFFICE

LOUIS STIENNEN, OF NEW HAVEN, CONNECTICUT, ASSIGNOR TO WINCHESTER REPEATING ARMS CO., OF NEW HAVEN, CONNECTICUT, A CORPORATION OF DELAWARE

DOUBLE-BARRELED FIREARM

Application filed April 10, 1929. Serial No. 354,089.

This invention relates to an improvement in double-barreled firearms and particularly to double-barreled firearms having two triggers, the object being to provide a simple, 5 convenient and reliable firearm of the type described in which the finger-reach, i. e., the distance between the finger-pieces of the respective triggers and the small of the stock, is substantially the same for both triggers.

10 A further object of my invention is to provide a firearm of the character referred to with a safety-mechanism designed to automatically prevent both triggers from being pulled into their firing positions at the same time.

15 A still further object of my invention is to provide a double-barreled firearm having two triggers, a slight draft upon either one of which will automatically hold the other 20 trigger against being pulled into its firing position.

With the above objects in view, my invention consists in a double-barreled firearm having certain details of construction and 25 combinations and arrangements of parts as will be hereinafter described and particularly recited in the claims.

In the accompanying drawings:

Fig. 1 is a broken view in side elevation of 30 a trigger-mechanism constructed in accordance with my invention, the trigger-mounting plate thereof being broken away and the triggers being shown in their normal positions;

Fig. 2 is a top or plan view thereof;

Fig. 3 is a vertical longitudinal sectional view through the trigger-plate and mounting-block and showing the right-hand trigger pulled rearward for releasing the firing- 40 mechanism of its complementary barrel and, at the same time, automatically locking the left-hand trigger against operation;

Fig. 4 is a view corresponding to Fig. 3 but showing the left-hand trigger pulled rearward in position to fire its complementary barrel and to effect the automatic locking of the right-hand trigger against similar rearward pull;

Fig. 5 is a transverse sectional view taken 50 on the line 5—5 of Fig. 1;

Fig. 6 is a detached perspective view of the right-hand trigger;

Fig. 7 is a corresponding view of the left-hand trigger; and

Fig. 8 is a similar but smaller-scale view 55 of the trigger-spacing plate.

In carrying out my invention as herein shown, I employ a trigger-mounting plate 10 which is adapted to be installed in the usual manner in a double-barreled firearm and is 60 provided with an upstanding mounting-block 11 formed with a longitudinal slot 12 extending from front to rear therethrough and intersecting at its rear end the forward end of a slot 13 in the said trigger mounting-plate 10.

Installed in the right-hand side of the slot 12 in the mounting-block 11 above referred to is a plate-like right-hand trigger 14 extending also downward through the slot 70 13 in the trigger-mounting plate 10 and having a forwardly-inclined depending arm 15 terminating in a knurled forwardly-facing finger-piece 16 located closely adjacent the underface of the said trigger-mounting plate.

Installed in the left-hand side of the slot 12 of the mounting-block 11 and extending downward through the slot 13 of the trigger-plate is a plate-like left-hand trigger 17 having a relatively-long forwardly-curved depending arm 18 terminating in a knurled forwardly-facing finger-piece 19. In order to prevent the triggers 14 and 17 and particularly their depending arms 15 and 18 from rubbing one upon the other, I interpose between the plate-like body-portions of the said triggers a flat sheet-metal spacing-plate 20, as shown in Fig. 5. 85

The right-hand trigger 14 is provided near its upper edge about midway of its length with a transverse bearing-passage 21 adapted to receive a transverse screw-stud 22 extending between the respective opposite side-walls of the mounting-block 11 and upon which the said trigger 14 rocks. 90

The under-edge of the right-hand trigger 14 is formed with an under-cut notch 23 adapted to receive and hold in place one arm 100

24 of a V-shaped sheet-metal trigger-spring 25, the complementary free arm 26 of which bears against the upper face of the trigger-plate 10, as clearly shown in Figs. 3 and 4, and 5 exerts a constant effort to swing the said trigger clockwise and hence maintain its finger-piece 16 in its forward or normal position. To limit the clockwise swinging movement of the trigger 14 under the urge of the 10 spring 25 I provide the said trigger with a stop-shoulder 27 which engages the forward wall 28 of the slot 13 in the said trigger-plate.

At its forward upper corner the right-hand trigger 14 is formed with a laterally-offsetting integral guard-lug 29 tapering downwardly and rearwardly to a relatively-sharp edge, as clearly shown in Fig. 6 of the drawings. Near its rear upper edge the said trigger 14 is provided with a sear-lifting nose 30 adapted to engage and lift the inwardly-turned finger 31 of the right-hand sear 32 of the firearm so as to release the firing-mechanism of the right-hand barrel (not shown) 25 controlled thereby.

The left-hand trigger 17 is provided near its forward end (Fig. 7) with a transverse bearing-opening 33 receiving a transverse screw-stud 34 extending between the respective opposite side-walls of the bearing-block 11 near the lower forward end thereof and providing for the pivotal mounting of the left-hand trigger 17 aforesaid.

Formed at the forward upper corner of the left-hand trigger 17 is a guard-nose 35 forwardly and upwardly tapered to a relatively-sharp edge and adapted, as will hereinafter appear, to co-act with the guard-lug 29 of the right-hand trigger 14.

40 The said trigger 17 is formed in its upper edge with an under-cut notch 36 receiving the lower arm 37 of a V-shaped sheet-metal trigger-spring 38, the complimentary arm 39 of which bears against the upper wall 40 of the slot 12 in the mounting-block 11 before referred to, and exerts a constant effort to swing the left-hand trigger 17 in a clockwise direction so as to maintain its finger-piece 19 in its forward or normal position. 45 The clockwise swinging movement of the left-hand trigger 17 is limited by providing it with a stop-shoulder 41 engaging the forward wall 28 of the slot 13 in the trigger-plate 10.

50 The said trigger 17 is also provided with a transverse clearance-slot 42 for the clearance of the screw-stud 22 upon which the right-hand trigger 14 rocks and is also formed at its rear upper end with a sear-lifting nose 43 adapted to engage and lift the inwardly-turned finger 44 of a left-hand sear 45 controlling the firing-mechanism (not shown) of the left-hand barrel of the firearm.

It will be noted from the drawings that the 55 finger-piece 16 of the right-hand trigger 14

lies above and slightly forward of the finger-piece 19 of the left-hand trigger 17 so that both of the said finger-pieces are located at substantially the same distance from the small of the stock (not shown) of the firearm, whereby the user of the gun, when once accustomed to the firearm, is not compelled to have his hand assume a different position in order to reach either of the respective triggers.

If the user of the arm wishes to first fire the right-hand barrel of the firearm in which my improved trigger-mechanism as incorporated, in preference to the left-hand barrel, he will engage his trigger-finger with the finger-piece 16 of the right-hand trigger 14 and draw rearward thereupon with the effect of rocking the said trigger counter-clockwise and causing the sear-lifting nose 30 thereof to engage the inwardly-turned finger 31 of the right-hand sear 32 and so release the firing-mechanism of the right-hand barrel, which may be of any approved type.

Coincidental with the upward movement of the sear-lifting nose 30 of the trigger 14 as just above described, the guard-lug 29 will be swung downward in front of the guard-nose 35 of the left-hand trigger 17, as shown in Fig. 3, and so prevent the said left-hand trigger from being rocked counter-clockwise to release the firing-mechanism of the left-hand barrel until such time as rearward draft upon the right-hand trigger 14 is relaxed and the same is restored to its normal position (Fig. 1) by its spring 25.

Conversely, should it be desired to first fire the left-hand barrel of the firearm in preference to the right-hand barrel thereof, the user will engage his trigger-finger with the finger-piece 19 of the left-hand trigger 17 and draw the latter rearward so as to rock the left-hand trigger counter-clockwise, with the effect of causing its sear-lifting nose 43 to engage and lift the inwardly-turned finger 44 of the left-hand sear 45 so as to release the firing-mechanism of the left-hand barrel of the firearm.

Coincidentally with the counter-clockwise movement of the left-hand trigger as just above described, the guard-nose 35 thereof will be moved beneath the guard-lug 29 of the right-hand trigger 14, as shown in Fig. 4 of the drawings, with the effect of preventing the descent of the said lug and hence preventing the right-hand trigger 14 from being swung counter-clockwise to fire the right-hand barrel controlled by it until such time as rearward draft upon the left-hand trigger 17 is relaxed and the same is restored to its normal position (Fig. 1) by the spring 38.

In the event that the user of the arm should be so careless as to span with his trigger-finger the finger-pieces 16 and 19 of both of the triggers and exert simultaneous rearward draft thereupon, the guard-lug 29 of the

right-hand trigger will be swung slightly downward and the guard-nose 33 of the left-hand trigger will be swung slightly upward so that their sharp terminals will be brought into engagement and positively prevent both of the triggers from being swung counter-clockwise. However, owing to the relatively sharp-edged character of the engaging terminals of the said guard-lug 29 and guard-nose 35, a slight excess movement of one trigger over that imparted to the other will disengage the sharp terminals and permit either the guard-lug 29 to descend or the guard-nose 35 to rise, but never both at the same time. If the guard-lug 29 is first to pass the co-acting guard-nose 35, the left-hand trigger 17 will be locked against clockwise movement, as shown in Fig. 3 of the drawings. If, on the other hand, the guard-nose 35 of the left-hand trigger passes the sharpened terminal of the said guard-lug 29, the latter will be prevented from descending and hence prevent the clockwise swinging movement of the right-hand trigger 14.

25 I claim:

1. A double-barreled firearm having two triggers, each controlling the firing-mechanism of one of the barrels thereof and each provided with a finger-piece; and guard-means comprising a pair of directly co-acting guard abutments respectively carried by the said triggers in position to be inter-engaged one with the other by a relatively-slight initial manual movement of either one of the said triggers to automatically and positively restrain the other trigger against movement into its firing position.

2. A double-barreled firearm having two triggers, each controlling the firing-mechanism of one of the barrels thereof and each provided with a finger-piece; and guard-means comprising a pair of co-acting wedge-shaped guard-abutments respectively carried by the said triggers and brought into play by a relatively-slight initial manual movement of either one of the same to automatically and positively restrain the other trigger against manual movement into its firing position, the said wedge-shaped guard-abutments having their respective apices directed one toward the other.

3. A double-barreled firearm having two triggers, each controlling the firing-mechanism of one of the barrels thereof and each provided with a finger-piece; and guard-means brought into play by a relatively-slight initial manual movement of either one of the said triggers to automatically and positively restrain the other trigger against movement into its firing position, the said guard-means comprising a guard-lug laterally offsetting from one of the said triggers and a co-acting guard-nose carried by the other of the said triggers.

4. A double-barreled firearm having two

triggers, each controlling the firing-mechanism of one of the barrels thereof and mounted for pivotal movement side by side about different centers; and guard-means comprising a pair of directly co-acting guard-abutments respectively carried by the said triggers in position to be inter-engaged one with the other by a relatively-slight initial manual movement of either one of the said triggers to automatically and positively restrain the other trigger against movement into its firing position.

5. A double-barreled firearm having two triggers, each controlling the firing-mechanism of one of the barrels thereof and mounted for pivotal movement side by side about different centers; and guard-means brought into play by a relatively-slight initial manual movement of either one of the said triggers to automatically and positively restrain the other trigger against movement into its firing position, the said guard-means comprising a guard-lug laterally offsetting from one of the said triggers into the path of movement of its complementary trigger and a co-acting guard-nose carried by the other of the said triggers.

In testimony whereof I have signed this specification.
